UNITED STATES PATENT OFFICE.

FREDERICK MANKEY, OF WILLIAMSPORT, PENNSYLVANIA.

DESIGN FOR A PANEL.

SPECIFICATION forming part of Design No. 17,224, dated March 29, 1887.

Application filed February 28, 1887. Serial No. 229,263. Term of patent 7 years.

To all whom it may concern:

Be it known that I, FREDERICK MANKEY, of Williamsport, Lycoming county, Pennsylvania, have invented and produced a new and original Design for Panels, of which the following is a specification, reference being had to the accompanying photographs, forming part hereof.

Figure 1 represents my new design, and Fig. 2 a modification thereof.

My design consists in the raised parallelogram A. Adjacent to said parallelogram and on opposite sides thereof are two narrower parallelograms, B and C. Adjacent to each extremity of the narrower parallelograms B and C is a square elevation, E F G H. Adjacent to each end of the parallelogram A are two square elevations, I J and K L. The elevations E I J F and G K L H are in rows transversely the panel. All of the aforesaid raised parallelograms and elevations have beveled or inclined edges and flat upper surfaces. Between each elevation and the elevations

adjacent thereto is formed a channel, as M. The elevations E I J F G K L H are of like size. Instead of a single row of square elevations, as E I J F and G K L H, on each side of the parallelograms A B C, as represented in Fig. 2, I may show two rows, as represented in Fig. 1, the additional rows being marked 25 E' I' J' F' and G' K' L' H'.

I claim -

1. The design for a panel, substantially as herein shown and described, which consists in the parallelograms A B C and square elevations E I J F G K L H. 35

2. The design for a panel, substantially as herein shown and described, which consists in the parallelograms A B C and the square elevations E I J F, E' I' J' F', G K L H, and G' K' L' H'. 40

FREDERICK MANKEY.
